GASOLINE NOZZLE PROTECTIVE DEVICE

William R. Anderson, Perrysburg, Ohio, assignor
to Champion Spark Plug Company, Toledo,
Ohio, a corporation of Delaware

Application September 17, 1953, Serial No. 26,842

Term of patent 3½ years

(Cl. D52—2)

To all whom it may concern:

Be it known that I, William R. Anderson, a citizen of the United States and resident of Perrysburg, in the county of Wood and State of Ohio, have invented a new, original, and ornamental Design for a Gasoline Nozzle Protective Device, of which the following is a specification, reference being had to the accompanying drawing, forming a part thereof.

In the drawing,

Fig. 1 is a view in elevation of a gasoline nozzle protective device embodying my new design with a gasoline nozzle shown in dotted lines to show my device in position of use;

Fig. 2 is a top plan view of the gasoline nozzle protective device;

Fig. 3 is a bottom plan view thereof; and

Fig. 4 is an end elevational view thereof.

I claim:

The ornamental design for a gasoline nozzle protective device, substantially as shown and described.
